UNITED STATES PATENT OFFICE.

ALEXANDER F. WINTERS AND BASIL R. CRAMPTON, OF GRAND RAPIDS, MICHIGAN.

LATCH.

Application filed November 29, 1926. Serial No. 151,279.

This invention relates to latches of the type which are used on refrigerators, cabinets, cupboards and the like. It is a primary object and purpose of the present invention 5 to provide a latch which may be swung in either direction from its normal central position, and which will be retained at the limit of its swing in either direction so that it may pass over the nose of a keeper and 10 be tripped by a projecting post or finger extending from the keeper, thereby releasing the latch for movement into engaging position with the hook of the keeper. By reason of the fact that the latch lever may be 15 swung in either direction, said latch, without change, may be used on doors swinging either to the right or to the left, and it is not necessary to keep stocks of the two kinds 20 of latches on hand nor is there any necessity of selecting any particular latch for either a right or a left hand swinging door.

In order that a latch, after attachment to the door, shall not be swung in the wrong direction and held therein, in which case it 25 would strike against the keeper to the detriment of the latch, a further object of the invention is to provide a simple means for insuring against any such occurrence. The means which we have provided is one that 30 can be made effective immediately prior to the attachment of the latch to the door and this can be done on the latch irrespective of whether it is to be attached to a door swinging to the right or to the left.

Still further objects of the invention are to provide a latch construction of the type outlined which is attractive in appearance and economical to manufacture, and in which the spring which is used to normally hold 40 the latch in operative position is housed within the body of the latch lever and in which the assembly of the parts is very simple and easy to accomplish. Many other objects and purposes than those stated together 45 with novel constructions for attaining the same will be apparent as an understanding of the invention is had from the following description taken in connection with the accompanying drawings, in which,

Fig. 1 is a front elevation of a latch made in accordance with our invention, the latch being attached to a door and a keeper therefor to a door casing, and with the upper side of the latch housing removed to disclose the interior construction.

Fig. 2 is a horizontal section through the construction shown in Fig. 1.

Fig. 3 is a vertical section through the latch and door shown in Fig. 1.

Fig. 4 is a view similar to that shown in Fig. 1, the latch being shown held in inoperative position, that which it occupies during the time that the door is open.

Fig. 5 is a side elevation of latch shown in Fig. 4, looking at the same from the left.

Fig. 6 is a perspective view of the base plate of the latch.

Fig. 7 is a perspective view of the several parts which make up the latch lever, the same being shown disassembled and with certain parts broken away for a better disclosure of the structure.

Fig. 8 is a view similar to Fig. 4, illustrating the latch but with a slightly different form of base plate which may be used to hold the latch against movement in one direction away from its normal central position.

Fig. 9 is a horizontal section through the construction shown in Fig. 8.

Fig. 10 is a vertical section through the latch and door, shown in Fig. 8, and

Fig. 11 is a perspective view of the base plate.

Like reference characters refer to like parts in the different figures of the drawings.

The latch proper is adapted to be attached to a door 1 and the keeper to the door jamb or casing 2. The keeper includes a base 3 which may be permanently secured to the door casing 2 by suitable screws and from which, near the lower end, a post 4 projects outwardly, terminating in an upwardly extending hook 5 which is formed at its outer edge with a downwardly and outwardly extending cam surface 6 and at its inner side with a downwardly and inwardly inclined wedging surface 7. Above the post 4, a post or finger 8 extends outwardly from the base 3, its outer end having a downwardly and inwardly inclined edge 9. The post or finger 8 is shorter than the keeper proper including the hook 5, so that the end of the latch lever may pass between the finger and the keeper hook.

The latch proper which is attached to the door includes an outer casing of sheet metal having a top or outer side 10 from which upper and lower inturned sides 11 extend,

each being then turned outwardly to make substantially flat attaching ears or flanges 12, through which screws are passed to attach the latch to the door 1. The housing 5 formed by the top 10 and sides 11 is completed at one side by a side 13, while the other side or that nearest the edge of the door is substantially open. The side 13 is also provided with an opening for the passage 10 of the latch lever.

Against the inner side of the top 10 a bar 14 is located horizontally and has its ends turned inwardly for a short distance, suitable tongues 16 being turned inwardly into 15 notches in the ends of the bar 14 from the ends of the housing so as to permanently secure the bar in place. A pivot pin 17 is fastened at one end to the bar 14 near the end 13 of the housing and extends therefrom 20 as best shown in Fig. 2.

The latch lever is formed from a piece of flat metal, the intermediate portion being made into channel form having a web 18 with inwardly extending parallel flanges 19. 25 At one end of the latch lever the metal is continued, bent outwardly and thence extended horizontally and formed into a handle 20 which lies outside of the latch housing or casing. The opposite end is likewise 30 formed into a keeper engaging portion 21, that is, the flanges of the channel are curved and bent inwardly toward each other and the space between the flanges closed at the end by an integral portion of the metal from which 35 the latch lever is made, all as fully shown in Fig. 7. A circular opening 22 is made, in the web 18 through which the post 17 passes and near said opening the web 18 is cut away to make an elongated opening 23, 40 at the outer end of which a tongue 24, integral with the web 18 is turned inwardly, this being also shown in Fig. 7.

Over the intermediate portion of the latch lever a member of sheet metal is placed comprising a central web 25 which lies directly 45 over the opening 23 and from which flanges 26 extend inwardly, one along side each flange 19 of the latch lever. At its outer end the web 25 is formed into two diverging 50 fingers 27, the ends of which are adapted to bear against the inner side of the side 13 of the housing when the latch lever is in its middle position as shown in Fig. 1. The outer side or web 25 has a tongue 28 struck 55 therefrom and turned inwardly which passes into the opening 23 in the latch lever. Between the two tongues 24 and 28 a coiled spring 29 under compression is located. It will be noted, referring to Figures 2 and 9, 60 that when the latch is assembled the web 25 and fingers 27 are arranged at an angle to the latch lever so that when the latch lever is mounted on the pivot 17 the tendency of the lever is to rock at its end 21 inwardly 65 toward the door or base plate which is lo-

cated at the inner side of the housing, this being caused by a component of the spring 29, due to the angular location of the fingers 27 and the web 25 as described. The opening 22 through the web 18 of the latch lever 70 is sufficiently large to permit the slight rocking movement which occurs.

The base plate 30 is a plate of sheet metal having a shape to fit the inner side of the housing and the attaching flanges 12 thereof. 75 The edge of the plate at the open outer end of the housing is equipped with a shelf member 31 of triangular form which is turned back on the shelf and lies flat thereagainst having opposite edges 32, one at the upper and one at the lower side of the shelf member. Also a short distance from the shelf member 31 two tongues 33 are turned back against the base plate and spaced a short distance from each tongue is an attaching finger 34 each adapted to fit in a suitable slot formed in the housing. This, however, is not a feature of the present invention. The base plate is attached to the housing by engaging fingers 34 in their slots and then passing a screw 36 into the pivot pin or post 17 through an opening 35 made in the base plate. It is also apparent that the necessary openings for passage of the screws which attach the latch to the door are provided in the base plate, as shown in Fig. 6. 85

In Figs. 8, 9 and 10 a slightly different form of base plate is provided and one which for many reasons is preferred. The only difference is that the plain base plate which is shown in Fig. 6 is cut so as to provide two spaced apart stops 37 which, when the latch is assembled, are flat and lie in the same plane with the plate but either one of which may be pushed above the plane of the plate for a short distance in a very simple manner, such as by pressing against the end of a stop with a screw driver. 95

The latch described is very practical and useful. When attached to a door, upon grasping the handle 20 and pulling downwardly and outwardly thereon the latch lever is swung about the pivot or post 17. The upper finger 27 bears against the side 13 of the housing whereupon the member to which the finger is attached is moved longitudinally of the latch lever and compresses the spring 29. When the lever has moved to its extreme upper position it passes by the upper edge 32 of the shelf member 31 and moves inwardly at its keeper engaging end so as to engage with the shelf when the latch lever is freed. The tongue 33 above the shelf member 31 in such case lies between the flanges 19 of the lever. The latch lever is held in its retracted position all of the time that the door is open. On closing the door the projecting end 21 of the lever strikes against the inclined edge 9 of the finger 8 on the keeper, whereupon the lever 105

105

115

120

125

130

is tripped and disengaged from the retaining shelf 31 and moves to engaging position with the hook 5 of the keeper, the spring forcing the same into wedging engagement with the inner wedging side 7 of the hook 5.

If the door, on the other hand, is a door swinging to the left the latch is merely turned over, whereupon what was the lower edge of the retaining shelf 32 becomes the upper edge and the lower finger 27 becomes the upper finger in the new position of the latch. The manner of holding the latch in retracted position and tripping it when the door is closed is the same.

It is apparent, of course, that with the construction of base plate as shown in Figs. 4, 5 and 6 the lever could be turned in the wrong direction and held in retracted position against the under edge 32 of the shelf 31. If this should occur, then on closing the door the projecting end 21 of the lever would strike against the keeper below the cam surface 6 thereof with likelihood of injury to the latch or keeper or the fastenings which secure the same to the door and door casing. It is, accordingly, preferred to use the base plate such as shown in Figs. 8 to 11, inclusive. With such base plate, one of the stops 37 may be pressed inwardly, as shown in Figs. 9, 10 and 11 and it will serve as a stop to prevent the lever moving to and being held in such undesired position. Either one of the stops 37 may be bent depending upon whether the latch is to be used on a right or left swinging door.

The construction is compact, simple to manufacture, very durable and efficient and is especially easy to assemble. The parts shown in Fig. 7 can be placed together without the use of tools, then the lever placed over the pivot or post 17 and the base plate attached by use of a single screw 6. The housing of the spring 29 makes a very compact and efficient structure. The invention is defined in the appended claims and is to be considered comprehensive of all forms of structure coming within their scope.

We claim:

1. In a latch, a covering casing, a latch bar pivotally mounted within the casing, a member slidably mounted on the latch bar having diverging fingers engaging against an end of the casing, and spring means disposed between said latch bar and said member normally holding the latch bar at a central position from which it may be rocked in either direction.

2. A latch comprising, a housing, a latch bar pivotally mounted within the housing, said latch bar having an elongated opening therethrough, a member slidably mounted on the latch bar having two diverging fingers at one end adapted to bear against an end of the housing and having a tongue ex-

tending into said opening in the latch bar, and a coiled spring disposed between said tongue and the opposite end of the spring bearing against the latch bar at an end of said opening.

3. A latch comprising, a housing, a latch bar pivotally mounted in said housing, said latch bar being of channel form having an outer web and inwardly extending spaced apart flanges, the web being cut away a short distance from the pivot to make an elongated opening, a portion of the web at one end of the opening being turned inwardly, a member of channel form located over the latch bar and having a tongue struck therefrom extending into the opening in the latch bar a distance from the tongue on said bar, a coiled spring under compression located between the flanges of said latch bar and having its ends bearing against said tongues, and diverging fingers extending from said member one to each side of the pivot of the bar and bearing at their ends against an end of the housing whereby the latch bar is normally held in central position.

4. In a latch, a support, a latch bar pivotally mounted thereon, a base plate located under the latch bar and having a shelf at one edge with opposite edges coming to a point, each lying at an angle to the horizontal, spring means housed within the latch bar, and means slidably mounted on the latch bar with which the spring means engages, said means mounted on the latch bar being formed with diverging fingers, the ends of which abut against said support to normally hold the bar in central position over said shelf.

5. A construction containing the elements in combination defined in claim 4, said base plate being formed with stop members lying in the plane of the plate and adapted to be pressed to one side of the plane of the plate so as to stop swinging movement of the latch lever in one direction, one of said stops being used to limit the swinging movement of the latch member in one direction and the other in the opposite direction.

6. In a construction of the class described, a metal covering housing, a base plate closing the inner side of the housing, a pivot pin disposed between the housing and base plate, a latch lever pivotally mounted on said pivot pin to swing to either side of a central horizontal position, said latch lever having an elongated longitudinal opening therethrough, a coiled spring located in said opening, a sheet metal member of channel form located over the latch lever and having a tongue struck inwardly therefrom extending into said opening in the latch lever and against which one end of the spring bears, and diverging fingers extending from one end of said member and lying at an angle to

the plane of said member, the ends of the fingers bearing against the inner side of the end of the housing.

7. A latch comprising, a covering housing, a base plate closing the inner side of the housing, a shelf member located at one edge of the base plate substantially midway between its upper and lower edges and having upper and lower shelf edges coming to a point and located at an angle to the horizontal, said shelf member also above and below the central horizontal middle line of said plate, having stop tongues cut from the plate and lying in the plane of the plate, either one thereof being adapted to be bent at its free end to one side of the plane of the plate, a pivot pin between the base plate and housing, a latch lever pivotally mounted to rock on said pin, and spring means cooperating with the latch lever to normally hold it in central horizontal position, said lever engaging with an edge of the shelf when swung in either direction away from its normal position sufficient to carry it beyond either edge of the shelf.

8. A latch comprising, a latch housing, a latch lever pivotally mounted in said housing, spring means housed within the latch, and an abutment member slidably mounted on the latch and engaging with said spring means and also with an end of the housing at two spaced apart points whereby the lever is normally held in an intermediate central position but may be swung in either direction away from such position.

9. A latch construction comprising, a pivotally mounted latch bar, shelf means under said bar having two edges with either of which the bar is adapted to engage when swung in opposite directions from a normal central position, spring means housed with-

in the latch bar, and means slidably mounted on the bar with which said spring means engages, combined with an abutment against which said slideable means engages to hold the latch bar in normal central position.

10. A latch construction comprising, a pivotally mounted latch bar, a member slidably mounted on the latch bar, having a finger extending therefrom and to one side thereof, a latch casing in which said bar is pivotally mounted against one end of which the free end of the finger bears, and spring means disposed between said member and the latch bar, substantially as and for the purposes described.

11. A latch comprising, a latch housing, a latch lever pivotally mounted in the housing, means associated with the latch member and housing and normally holding said latch lever in a central position from which it may be rocked in either direction, a base plate closing the inner side of the housing, and stop means on said base plate for preventing swinging movement of the lever in one direction away from its normal position, but permitting free movement thereof in the opposite direction.

12. A latch comprising, a latch housing, a latch lever pivotally mounted in said housing, means associated with the lever and housing for yieldingly holding the lever in a central normal position, a base plate closing the inner side of the housing, and bendable stops on said base plate, one at each side of the lever, either one of which may be bent into the path of movement of said lever.

In testimony whereof we affix our signatures.

ALEXANDER F. WINTERS.
BASIL R. CRAMPTON.
